ANTI-ROLL STABILIZERS OF SHIPS

Franz Süberkrüb, Chilehaus C VI, Hamburg 1, Germany
Filed May 6, 1960, Ser. No. 27,401
2 Claims. (Cl. 114—126)

The invention relates to an arrangement for damping the rolling movement of ships.

It is the object of the invention to eliminate the disadvantages which are inherent particularly in installations attempting the anti-roll stabilization by means of fins, which are in use extended on both sides of the ship from appropriate fin chambers and produce moments opposed to the rolling of the ship by automatically controlled rotary movements.

There is a known device of this kind, in which the fins are each connected with a fin shaft, having two bearings. The first of these bearings is located within the fin chamber, serving to receive the fin in the retracted, i.e., in the resting position, while the second bearing is located within the hull of the ship. Between the first and the second bearing, the fin shaft passes through a stuffing box in the wall of the fin chamber adjacent to the hull. Both bearings are located in bodies, so-called traverses, which, in order to make possible the movement of the fin out of the chamber, or its retraction into the same, are slidably located on slides or rails, which are positioned athwartships.

This design has the disadvantage of requiring much room athwartships, because each fin shaft moves from the fin chamber towards the inside of the ship by the same amount, by which the fin moves into the fin chamber, so that a space sufficient for this movement must be provided.

This disadvantage of requiring, for the reasons just indicated, in addition to the space for the fin chambers themselves, also a space equal to the length of the fin movement, may be avoided if, according to the invention, an anti-roll stabilizer is used, consisting of: fin chambers, arranged on each side of the ship in the hull near the shell, located athwartship, and having an opening towards the outside of the ship; sliding tracks or rails, arranged athwartships in each of said fin chambers; a body slidably displaceable on said slide tracks; a fin carried by said body, capable of being made to protrude through said opening in the fin chamber towards the outside into its operating position by shifting said body towards one side, while being retracted into the rest or inoperative position in the fin chamber by shifting this body towards the other side; actuating means for moving the displaceable body, comprising a motor, located outside the fin chamber and within the hull and transmission means for connecting said motor to said slideable body; means for rotatably locating said fin on the slideable body; actuating means for rotating the fin, comprising a motor located outside the fin chamber within the hull, and transmission means for connecting said motor to the fin, and for producing the rotating movement of the fin, whereby all transmission means, between the first motor and the slideable body, and between the second motor and the rotatable fin, insofar as these components take part in the to-and-fro movement of the slideable body, are located in the fin chamber or in a space communicating therewith, remaining therein in all operating positions.

The invention will be further described, by way of example, with reference to the accompanying drawing, of which FIGS. 1 to 4 show one embodiment of the invention, in which:

FIG. 1 is a schematic, partly sectional view of a fin chamber with the fin in operating position and its actuating means, seen in the direction of the longitudinal axis of the ship;

FIG. 2 is a plan view of FIG. 1 omitting the plate 14;

2

FIG. 3 is an end view of the fin chamber with actuating means, seen from within the ship; and

FIG. 4 is a view of the fin chamber, similar to that of FIG. 3, but seen from the opposite end.

5 With reference to FIGS. 1 to 4, one fin chamber 14 is arranged on each side of the ship in the hull, adjacent to the shell 40, and located athwartships, and having opening 41 in the ship plating.

Tracks or rails 4, 5 are located athwartships in said fin chamber 14, and a body 3 is slidably mounted on said tracks so as to be movable to and fro therealong. Said body 3, which may also be called a traverse, carries the fin 1 mounted on an axle 2, which, if the body 3 is displaced outboard of the ship, is made to protrude through the opening 41 of the fin chamber 14 and to move into its operating position, and vice versa, by sliding said body inboard the fin is retracted into the fin chamber and into the inoperative position. Between the two tracks 4 and 5, a bearing block is fitted to the base of the fin chamber 14, in which a chain wheel 21 is rotatably journaled. A second, co-operating sprocket wheel 20 is keyed to a shaft 25. The space in which said sprocket wheel 20 is located communicates with inside of the fin chamber 14. The shaft 25, carrying the sprocket wheel 20, passes from the fin chamber through a stuffing box into the interior of the ship and may be rotated from there, through a suitable transmission 24, by an electric motor 23, in one or the other direction. A chain 22 passes over the sprocket wheels 20 and 21; this chain, or its ends, are attached to the body 3. In this way the body 3 may be pulled by means of said electric motor 23 towards the right or left, according to the direction of movement of the chain 22.

The fin 1 may be rotated about an axle or shaft 2, which is firmly fixed in the body 3. It may, however, also be keyed onto said axle 2, in which case said axle is rotatably mounted in the body 3.

The fin 1 is rotated by a hydraulic motor, which may comprise a cylinder 6 with a pressure-medium-operated piston, the piston rod 7 of which is pivoted to a crank 8, 40 which is fixed to a shaft 9. This shaft 9 is rotatable in the fixed bearings 10, 11 and 12, and extends from within the ship, through a stuffing box 13, into the fin chamber 14. It is arranged parallel to the tracks 4, 5 and is mounted in such a way that it is not displaced along its longitudinal axis. Said shaft 9 carries two spaced cranks 15 and 16 of equal size and extending in the same direction, which are rigidly fixed thereto, so that they cannot shift or rotate relative thereto. The two cranks 15 and 16 carry on their free ends a common rod 17 parallel to shaft 9. A link 18 is fitted to said rod 17 so that it may rotate thereon and be longitudinally displaced, being pivoted to a pin 19 on its other end; this pin 19 is firmly attached to the fin 1.

If the crank 8 is rotated in one or the other direction 55 by the piston moving in the cylinder 6, the just described transmission will also cause a rotation of the fin 1 in the corresponding one or the other direction.

If the body 3 with the fin 1 moves along the track 4, 5 towards the left, the link 18 is taken along by the fin 1, 60 sliding on the rod 17 towards the left; if, however, the body 3 with the fin 1 moves towards the right, the head or collar 42 of the pin 19 causes the link 18 with the fin 1 to move towards the right.

What I claim is:

1. An arrangement for damping the rolling of ships, comprising athwartship fin chambers provided one on each side of the ship within the hull adjacent to the shell, and having an opening outwardly of the ship, tracks in each of said fin chambers extending athwartship, a body 65 slidably mounted on said tracks, a fin carried by said body adapted to be pushed out into operating position outside the ship through said opening in the fin chamber upon

sliding said body towards said opening and retracted into non-operative position within the fin chamber by sliding said body away from said opening, said fin being mounted for rotation on an axis generally parallel to said tracks, actuating means for sliding said body along said tracks, including a first motor located outside the fin chamber and within the hull of the ship, and transmission means operatively connecting said first motor to said body for sliding said body on said tracks, means rotatably mounting said fin on said body, actuating means for rotating the fin, comprising a second motor located outside the fin chamber and within the hull of the ship, a shaft rotatable in either direction within the fin chamber and lying parallel to and spaced from the axis of rotation of said fin, said shaft being fixed against longitudinal movement in the fin chamber, means slidably connected to said shaft operatively connecting said shaft to said fin whereby rotation of said shaft rotates said fin, and transmission means operatively connecting said second motor to said shaft for producing rotational movement of the shaft.

2. An arrangement for damping the rolling of ships, comprising athwartship fin chambers provided one on each side of the ship within the hull adjacent to the shell, and having an opening outwardly of the ship, tracks in each of said fin chambers extending athwartship, a body 25 slidably mounted on said tracks, a fin carried by said body adapted to be pushed out into operating position outside the ship through said opening in the fin chamber upon sliding said body towards said opening and retracted into non-operative position within the fin chamber by sliding said body away from said opening, said fin being mounted for rotation on an axis generally parallel to said tracks, actuating means for sliding said body along said tracks, in-

cluding a first motor located outside the fin chamber and within the hull of the ship, and transmission means operatively connecting said first motor to said body for sliding said body on said tracks, means rotatably mounting said fin on said body, actuating means for rotating the fin, comprising a second motor located outside the fin chamber and within the hull of the ship, a shaft rotatable in either direction extending into the fin chamber and lying parallel to the axis of rotation of said fin, said shaft being fixed against longitudinal movement in the fin chamber, means which operatively connect said shaft to said fin whereby rotation of said shaft rotates said fin, including two crank arms fixed to said shaft at a distance from each other along the said shaft and having equal length and extending in the same direction, a rod extending between said cranks, a link, one end of which is rotatable in and longitudinally slidable with respect to said rod, and a pin on said fin to which the other end of said link is pivoted, said pin being located on the fin at a distance from the axis of the fin so that it forms a lever arm to effect the rotational movement of the fin whereby rotation of said shaft effects rotation of said fin.
